UNITED STATES PATENT OFFICE.

MARION S. SABEL, OF MILWAUKEE, WISCONSIN.

FOLDING FRUIT-STAND.

1,235,248.

Specification of Letters Patent. Patented July 31, 1917.

Application filed October 9, 1916. Serial No. 124,713.

To all whom it may concern:

Be it known that I, MARION S. SABEL, a citizen of the United States, residing at the city of Milwaukee, county of Milwaukee, 5 and State of Wisconsin, have invented new and useful Improvements in Folding Fruit-Stands, of which the following is a specification.

My invention relates to improvements in 10 that class of folding fruit stands, for which Letters Patent of the United States, No. 914606 was issued to John H. Sabo, March 9, 1909. By the device shown in said patent three separate receptacles 11 were shown 15 one above another, which receptacles were first adapted to be removed when the frame was folded rearwardly, as indicated by dotted lines in one of the figures. By the present improvement a single receptacle 20 only is used, and this receptacle is supported upon two inclined end bars which are located near the upper end of the foldable frame, and both of said end bars are provided with recesses adapted to engage pins 25 projecting from the sides of the vertical bars, whereby the frame is prevented from being folded, said inclined bars serving the two-fold purpose of supporting said receptacle and preventing the device from being accidentally folded from the position 30 shown in Figures 1 and 2 to that indicated in Fig. 3.

My invention is further explained by reference to the accompanying drawing, in 35 which—

Fig. 1 represents a perspective view of the device, with the receptacle supported upon said inclined end bars.

Fig. 2 is a vertical section, drawn on line 40 2, 2 of Fig. 1, and

Fig. 3 represents the device as folded, preparatory to being shipped or stored away for future use.

Like parts are identified by the same reference numerals throughout the several views.

1 represents the receptacle which is supported upon the two inclined end members 2. The end members 2 are each provided with a plurality of recesses 3, which recesses are adapted to engage the later-

ally projecting pins 4 and 5, said pins being permanently connected at each end of the device to the vertical members 6 and 7. The inclinable end members 2 are 55 each pivotally connected at their lower ends by the pivot 8 to one of the vertical corner standards 9.

The central standard 7 is pivotally connected with the horizontal end members 10, 60 11 and 12 by pivotal bolts 13, while said vertical corner posts or standards 9 are pivotally connected with said horizontal members 10, 11 and 12 by pivotal bolts 14, 14, said horizontal members 10, 11 and 12 being 65 pivotally connected at their opposite ends with the vertical standard 6 by pivotal bolts 15, 15, 15. The inclinable members 2 are preferably connected together by the horizontal members 16, 16, 16 said members 16 70 being permanently connected with said inclinable members by rivets 17 of ordinary construction.

The front corner posts 9 are preferably connected together by a plurality of horizontal members 18, 18, 18, which members 18 are also permanently connected at their respective ends with said corner posts or standards 9 by a plurality of rivets 19, 19, 19. The rear or longer corner posts or 75 standards 6 are connected together by a plurality of horizontal members 20, 20, 20, and said members 20 are permanently connected with said corner posts or standards by rivets 21, 21, 21. 80 85

Preparatory to folding my device the receptacle 1 is first removed when the upper end of the inclinable end members 2 is raised and thrown forwardly, when all of said bars and posts are inclined forwardly as indicated in Fig. 3, whereby said device may be retained in a compact condition preparatory to being stored or shipped.

Having thus described my invention what I claim as new and desire to secure by Letters Patent, is:—

In a device of the described class, the combination of a plurality of vertical front, rear, end and corner standards, a plurality of horizontal front, rear and end members connected together by pivots, two inclinable end members each provided upon 100

its lower edge with recesses, said inclinable end members being each pivotally connected at its lower end to the front corner standards, and adapted when inclined rearwardly to perform the two-fold function of supporting a receptacle and locking said folding members together.

In testimony whereof I affix my signature in the presence of two witnesses.

MARION S. SABEL.

Witnesses:

O. C. WEBER,
JAS. B. ERWIN.
